UNITED STATES PATENT OFFICE.

RAYMOND E. SERVIS AND FREDRICH J. RODE, OF CHICAGO, ILLINOIS, ASSIGNEES TO MARQUETTE TOOL & MFG. COMPANY, OF CHICAGO, ILLINOIS, A CORPORATION OF ILLINOIS.

BLANK-HOLDING MEANS.

Application filed December 6, 1924. Serial No. 754,349.

To all whom it may concern:

Be it known that we, RAYMOND E. SERVIS and FREDRICH J. RODE, citizens of the United States, residing at Chicago, in the county of 5 Cook and State of Illinois, have invented certain new and useful Improvements in Blank-Holding Means, of which the following is a specification.

This invention relates to spring pressure 10 cushions for use in drawing in one operation, metal shapes or shells of a greater depth than is ordinarily possible to draw in one operation, and is particularly adapted though not necessarily limited in its use 15 in connection with what is termed a single action mechanical press.

In presses of this character there is provided a plurality of draw rings or blank holding means which co-operate with the 20 die, the blank being held between the draw ring or blank holding means and the ram during the forming or the shaping of the article. These draw rings are usually arranged one within the other, one of the rings 25 being held by spring pressure, against operation while the other ring is moved during the first portion of the cycle of operation of forming or shaping the blank over the stationary die and over the other die 30 ring.

After the completion of the first portion of the cycle of operation in forming or shaping the article and during the same stroke of the ram, the article is further shaped over 35 the stationary die, the inner draw ring being then moved against the spring pressure acting thereupon.

The fluid pressure upon the inner draw ring must of necessity be of such a degree 40 that the ring will not be moved during the first portion of the formation of the article, with the result that during that portion of the cycle of operation of the press in which the inner draw ring is moved, the 45 ram must overcome the excess spring pressure to complete the formation or shaping of the article. This results in a strain upon the crank shaft and clutches and reduces the capacity or scope of the press.

50 It is one of the objects of the present invention to overcome these difficulties and objections and to provide improved means to positively lock in a fixed position one of the blank holding members or draw rings while

the other member or blank holding means 55 is allowed to remain movable under the action of the ram, and to provide improved means for unlocking or releasing the locked member to allow it to move at a predetermined point or time in the cycle of operation of the press. 60

A further object is to provide improved means operating automatically to lock one of the blank holding means against movement and to automatically unlock or release 65 the blank holding means for movement.

To the attainment of these ends and the accomplishment of other new and useful objects as will appear, the invention consists in the features of novelty in substantially the 70 construction, combination and arrangement of the several parts hereinafter more fully described and claimed and shown in the accompanying drawings illustrating this invention, and in which 75

Figure 1 is a vertical longitudinal sectional view of a blank holding means constructed in accordance with the principles of this invention and showing the parts in their initial or starting position in the forming 80 of the article.

Figure 2 is a view similar to Figure 1 showing the parts in another position.

Figure 3 is a detail view, partly in section and partly in elevation taken on line 85 3—3, Figures 1 and 3.

Figure 4 is a detail horizontal sectional view taken on line 4—4, Figure 1.

Referring more particularly to the drawings the numeral 10 designates the bolster plate of a press, having mounted thereupon 90 a stationary die member 11, with which a cutting member 12 co-operates.

Co-operating with the die is another die member 13, carried by the ram or a movable part of the press, and this die member 13 95 co-operates with the member 12 to cut or shear the material 14 and is so shaped that it will pass between the dies 11 and 12 to shape the material over the die 11, all in a manner as well known in this art.

100 Encompassing the die 11 are a plurality of draw rings or blank holding members 15—16, one arranged within the other, and these members 15 and 16 are respectively supported by means of pins 17 and 18 that 105 pass loosely through the bed or bolster plate 10.

Supported below the bolster plate 10 is a spring cushioning device, which is supported preferably by means of a bolt or member 19 secured by one extremity to the bed or bolster plate 10. Supported by the other extremity of the bolt 19 is a plate 20 held in position by means of a nut or collar 21 threaded upon the end of the bolt 19 and which nut or collar 21 co-operates with a shoulder 22 on the bolt 19.

The plate 20 is spaced for any desired distance below the bolster plate 10, and encompassing the bolt 19 is a sleeve or collar 23 upon the top of which the pins 17 rest.

15 The collar is of any desired length and is supported by means of a coil spring 24 which encompasses the bolt 19, one end of the spring engaging the collar 23 and the other end engaging a nut or adjustable collar 25 carried by the bolt 19, and by means of which collar 25 the normal tension of the spring 24 may be varied.

15 Encompassing the sleeve or collar 23 is another collar 26 which carries an adjustable member 27 adjacent the lower face of the collar. Encompassing the spring 24 and the bolt 19 is another spring 28, one end of which engages and rests against the member 27 and the other end engages and rests against the plate 20. The pins 18 engage and rest upon the collar 26 and the spring 28 normally tends to hold the collar 26 elevated, and the collar is adapted to be depressed against the tension of the spring 28 in a manner to be hereinafter described. By adjusting the member 27 with respect to the collar 26 the normal stress of the spring 28 may be varied.

20 During the operation of the press when the member 13 descends the blank holding means 16 is depressed against the stress of the spring 28 through the medium of the pins 18 during one portion of the operation of the press, and during another portion of the 45 operation of the press, the blank holding means 15 is depressed against the stress of the spring 24 through the medium of the pins 17.

25 During a portion of the operation of the machine and while the blank is being formed during the shaping of the article over the die 11 and blank holding means 15, it is desirable to lock the blank holding member 15 against operation, and this is accomplished in the following manner.

30 Supported by the plate 20 is a bracket 29 which depends therebelow. Links 30—31 are pivotally connected by one extremity as at 32. The free end of the link 30 is pivotally connected as at 33 with the bracket 29. The free end of the link 31 is pivotally connected as at 34 to a rod 35 which passes loosely through the plate 20 and is connected as at 36 with the sleeve or collar 23, a lost motion such as a slot 37 being prefer-

ably provided at the pivot 34 to permit of the proper operation of the links.

The links 30 and 31 and rod 35 are of such lengths that when the collar 23 is at the limit of its upward movement or in the position shown in Figure 1, the pivots 32, 33 and 34 will be in alinement and the collar 23 will be locked against movement as will also the member 15.

The member 15 is locked against operation until a predetermined time in the cycle of operation of the press, that is until the completion of the formation of the article over the die 11 and member 15.

35 Any suitable means may be provided for releasing the locking mechanism, such as a bar or rod 38 which passes loosely through a lug or projection 39 carried by the collar 26 and also loosely through the plate 20.

A nut 40 is carried by the rod 38 on one side of the projection 39 and a nut 41 is carried by the rod on the other side of the projection 39.

The nut 40 serves as a means for supporting the rod 38 and for raising the same to permit the locking mechanism to become active when the collar 26 is raised by the stress of the spring 28.

40 When the collar 26 is depressed against the stress of the spring 28 the lug or projection 39 will engage the nut 41 to shift the rod 38 downwardly causing the extremity of the rod to engage a pin or plunger 42, moving the latter forwardly and into contact with the link 31 on one side of the pivot 32 so as to knuckle the links 30 and 31 and thereby unlock the blank holding member 14 and permit it, together with the collar 23 to be lowered against the stress of the spring 24.

45 The end 43 of the rod 18 and the extremity 44 of the pin or plunger 42 are preferably rounded to permit ease in operation and if desired the pin or plunger 42 may be provided with an adjustable extremity 45 in the form of a screw or the like for varying the length of the plunger and this screw 45 may be held in position by means of a lock nut 46.

50 It is thought that the operation of this invention will be clearly understood from the foregoing but briefly stated it is as follows. Assuming the parts to be in the position shown in Figure 1, and when the die 13 is lowered the material 14 will be cut by the dies 13 and 12. The blank holding means 16 will then be lowered by the die 13 against the stress of the spring 28 until the material has been partially shaped and until the material is shaped over the die 11 and blank holding means 15. After the completion of this step in the shaping of the article the projection 39 on the collar 36 will engage the nut 41 to force the bar or rod 38 downwardly and the plunger or pin 42 forwardly.

The latter will engage the link 31 to knuckle the links 30 and 31, thereby unlocking the blank holding member 15.

5 A further operation of the die 13 in the same direction will cause the blank holding means 15 to be depressed so that the article may be finished or shaped over the die 11 and the blank holding means 15 will then be depressed against the stress of the 10 spring 24.

When the die 13 is withdrawn the collars 26 and 23 will be moved upwardly by the stress of the springs 28 and 24. This movement of the collar 23 will straighten the links 30-31 with respect to each other through the medium of the rod 35 until the pivots 32, 33 and 34 are brought in alignment to again lock the blank holding means 15.

20 Upon the upward movement of the collar 26 the lug or projection 39 will engage the nut 40 to raise the bar or rod 38 so as to permit the pin or plunger 42 to be retracted.

While the preferred form of the invention 25 has been herein shown and described it is to be understood that various changes may be made in the details of construction and in the combination and arrangement of the several parts, within the scope of the claims, 30 without departing from the spirit of this invention.

What is claimed as new is:—

1. A draw press including a plunger, a plurality of separate spring controlled blank holding means adapted to successively co-operate with the plunger to clamp the work, and means operable to positively lock one of the blank holding means against operation during the operation of the other blank holding means, the last recited means including a toggle like device and means operable to knuckle the said toggle device to release the blank holding means locked thereby.

45 2. A draw press including a plunger, a plurality of separate spring controlled blank holding means adapted to successively co-operate with the plunger to clamp the work, means operable to positively lock one of the blank holding means against operation during the operation of the other blank holding means, the last recited means including a toggle like device, and means controlled in its operation by the actuation 50 of one of the said blank holding means for knuckling the said toggle to release the blank holding means locked thereby.

55 3. A draw press including a plunger, a

plurality of blank holding means adapted to successively co-operate with the plunger 60 to clamp the work, springs individual to the blank holding means and against the stress of which springs the respective blank holding means is operable under the stress of said plunger, a toggle like construction 65 operatively connected with one of the blank holding means for locking the latter against operation during the operation of the other blank holding means, and means responsive to the operation of the said other blank 70 holding means for knuckling the said toggle device to release the blank holding means that is locked thereby.

4. A draw press including a plunger, a plurality of blank holding means adapted 75 to successively co-operate with the plunger to clamp the work, springs individual to the blank holding means and against the stress of which springs the respective blank holding means is operable under the stress of said plunger, a toggle like construction 80 operatively connected with one of the blank holding means for locking the latter against operation during the operation of the other blank holding means, a plunger operable upon the said toggle device for knuckling the latter, and a shifting device operable 85 automatically at a predetermined time in the cycle of operation of the press for actuating the said plunger.

5. A draw press including a plunger, a plurality of blank holding means adapted 90 to successively co-operate with the plunger to clamp the work, springs individual to the blank holding means and against the stress of which springs the respective blank holding means is operable under the stress of said plunger, a toggle like construction 95 operatively connected with one of the blank holding means for locking the latter against operation during the operation of the other blank holding means, a plunger operable 100 upon the said toggle device for knuckling the latter, a shifting device operable at a predetermined time in the cycle of operation 105 of the press for actuating the said plunger, and means for varying at will the time in the cycle of operation of the press at which the said plunger is shifted by the said shifting device.

In testimony whereof we have signed our names to this specification on this 28th day of November, A. D. 1924.

RAYMOND E. SERVIS.
FREDRICH J. RODE.
